UNITED STATES PATENT OFFICE.

JOHN A. RATHBONE, OF DETROIT, MICHIGAN, ASSIGNOR TO THE UNITED STATES HEATER COMPANY, OF SAME PLACE.

DESIGN FOR A WATER-HEATER SECTION.

SPECIFICATION forming part of Design No. 27,721, dated October 12, 1897.

Application filed May 5, 1897. Serial No. 635,270. Term of patent 14 years.

To all whom it may concern:

Be it known that I, JOHN A. RATHBONE, a citizen of the United States, residing at Detroit, in the county of Wayne and State of Michigan, have invented and produced a new and original Design for a Water-Heater Section, of which the following is a specification, reference being had therein to the accompanying drawings.

5 This invention relates to an original design in water-heater sections and is shown in the accompanying drawings.

10 Figure 1 is a top plan of a section according to my design. Fig. 2 is a horizontal sectional view thereof. Fig. 3 is a perspective view, and Fig. 4 is a vertical sectional view.

15 As shown in the drawings, the design con-

sists of the section having the curved outer face and rounded or inwardly-curved top, as at G, forming a ring-segment at the top. The 20 inner faces are formed with the curved lobes E', having the inclined lower face.

Having thus described the invention, what is claimed as new, and desired to be secured by Letters Patent, is—

25 The design for a water-heater section, substantially as shown and described.

In testimony whereof I affix my signature in presence of two witnesses.

JOHN A. RATHBONE.

Witnesses:

JAMES WHITTEMORE,
M. B. O'DOGHERTY.
